CLOCK

Alan E. Koplar, Chicago, Ill.

Application July 12, 1951, Serial No. 15,842

Term of patent 14 years

(Cl. D42—7)

To all whom it may concern:

Be it known that I, Alan E. Koplar, a citizen of the United States and a resident of Chicago, in the county of Cook and State of Illinois, have invented a new, original, and ornamental Design for a Clock, of which the following is a specification, reference being had to the accompanying drawing, forming part thereof.

In the drawing:

Figure 1 is a front elevational view of a clock, showing my new design;

Fig. 2 is a side elevational view of said clock; and

Fig. 3 is a top plan view of said clock.

I claim:

The ornamental design for a clock, as shown.
ALAN E. KOPLAR.
